OF NEW YORK, N. Y.

BLANK-FORM BOOK.

1,115,602.

Specification of Letters Patent.

Patented Nov. 3, 1914.

Application filed December 31, 1913. Serial No. 809,648.

To all whom it may concern:

Be it known that I, ALEXANDER M. SINCLAIR, a citizen of the United States of America, and resident of New York, in the 5 State of New York, have invented certain new and useful Improvements in Blank-Form Books, of which the following is a specification.

The object of the present invention is to 10 provide a book or pad of blank forms, such for example as bonds, certificates, checks, notes, receipts, vouchers or other forms, the individual sheets of which are so bound together as to permit ready removal in regular 15 order from the top of the pad, but which do not permit removal in integral condition of any intermediate sheet below the top sheet. This object is accomplished by binding the individual form sheets at one end 20 into a block or pad, by means of a strip of binding muslin, paper, or similar appropriate material or substance, which extends around the end and partly along each of the two vertical sides of the pad to a point 25 at which the individual sheets are each provided with a notch or nick in its edge. The weakened or perforated line across the sheet dividing the stub from the check proper is located within the binding, namely between 30 the said nick or notch and the end of the pad bound by the cloth. The result is that when carefully removed at the top, an entire check may be detached at the line of weakening, as intended, leaving the stub. But when 35 it is attempted to remove any check below the topmost one, the portion of the same between the stub and the nick being held by the bound check or checks above and by the cloth binding at the edges, cannot be detached, and the check tears, starting in at 40 one edge where the binding cloth terminates, said tearing being facilitated by the location at that point of the notch in the check where it starts to tear. The weakened line 45 is located a substantial distance to the rear of the end of the binding, whereby access to the signature stub of a subjacent check cannot be had without removing the signature 50 stub of the next superposed check.

In the accompanying drawing, Figure 1

is a top-view of a pad of forms, embodying the invention. Fig. 2 is a side-elevation of the same, and Fig. 3 is a horizontal section on line 3—3 of Fig. 2.

Similar reference numerals indicate corresponding parts in all the figures.

The individual sheets are superposed and bound at one end 10 by a strip of muslin or other strong cloth binding material 30 glued to the sheets with a suitable padding composition. The strip extends along the vertical sides 11 and 12 of the pad adjacent said end and is likewise glued at said sides to the sheets. The line 13 of weakening separating the coupon or stub portion 14 from the body or main portion 15 of the sheet extends across the sheet from top to bottom, at a point between the end 10 of the sheet and the terminations of the binding material at the vertical sides of the pad, and is preferably removed back a considerable distance from said ends or terminations 16, 17, so as to be spaced therefrom. At the places 16, 17, where the binding terminates, is made in each sheet, at top and bottom of the sheet, a nick or notch, the same being cut by any suitable tool or machine in the course of manufacture of the pad or after the same is otherwise completed. These notches, 18, 19, are not of such depth into the body of the sheet as to interfere in any way with the proper handling of the same when detached. They may be angular in form as shown, or they may be of any other shape breaking the continuity of the edge of the sheet. A simple slit in the paper inward from the edge, will serve the same purpose, as also will a single perforation adjacent the edge, or a line of perforations across the sheet. For detaching sheets consecutively from said pad, the free end 21 of the main portion 15 of the uppermost sheet is grasped by the hand. The sheet is then lifted by said free end until the portion 22 of the sheet between the ends 16, 17, of the binding cloth and the line of weakening 13 becomes loosened and detached from the binding. Then by pulling the sheet angularly relatively to said line of weakening 13, the sheet is caused to tear on said line whereby

the main portion is detached, leaving the stub 14.

When it is attempted to detach an intermediate sheet, by an angular pulling of the 5 same, the strain does not reach the line of weakening 13, because that portion 22 of the sheet between the ends 16, 17, of the binding and the line of weakening 13 is not detached from the binding and cannot be detached 10 without first detaching the overlying sheets.

The sheet attempted to be removed is therefore firmly held, and the angular strain thereon causes the same to tear off approximately on the line 20 between the notches

15 18, 19, or on any rough line from the notch where the tear starts to the other side of the sheet. Thus the piece of paper which is obtained comprises only a part of the main form or blank, which is useless in itself, and 20 which shows by the part remaining in the pad that the same was irregularly removed. In Fig. 2 is shown at 23 the space remaining when such irregular removal of a sheet is made.

25 As a further protection and to show that the sheet so irregularly removed is not complete, a safety numeral may be printed thereon, which may be the same numeral as the consecutive number of the blank-form in 30 its series. Such a numeral is shown at 24, the number in the case of the wrongfully detached sheet being 2570. A part of the numeral, for example the first two figures, are printed on that portion 22 of the sheet which 35 must remain, while the remainder, the figures 70, is printed on the main portion 15 of the sheet, at the other side of the notch from the figures 25. The two portions make up the complete number of the form, which 40 is shown complete at the point 26 on the main portion 15 of the sheet. Thus by the fact that the number is incomplete at the left-hand corner of the wrongfully detached sheet, attention is called to the fact that the 45 sheet in itself is incomplete.

It is obvious that any desired blank forms can be made up in the manner shown, that is to say, the invention may be applied to any form of blank requiring security against 50 detachment out of regular order. The portion 22 of the sheet may be of such size as to receive a signature or other matter necessary to give validity to the whole form, such validating matter 27 being placed on the 55 sheets before they are padded, and being therefore unobtainable thereafter with any sheet not detached in regular order.

The invention provides a convenient means of guarding against the irregular use 60 of consecutively numbered blank or partially filled forms, and is an efficient aid in the orderly transaction of business and accounts by use of such forms.

I claim:

1. A blank-form book or pad, comprising 65 a plurality of superposed form sheets having a line of weakening near one end, notches in the top and bottom edges of the sheets, and means binding the sheets together at their edges at the vertical sides of the pad, 70 at said end, and between said end and said notches, said binding extending to the notches and including the portion of the sheet between the same and said line of weakening and said line of weakening being 75 located a substantial distance to the rear of the front end of the binding.

2. A blank-form book or pad, comprising 80 a plurality of superposed form sheets having a line of weakening near one end, notches in the top and bottom edges of the sheets, and means binding the sheets together at their edges at the vertical sides of the pad, 85 at said end and between said end and said notches, said binding extending to the notches and including the portion of the sheet between the same and said line of weakening and said line of weakening being located a substantial distance to the rear of the front end of the binding. 90

3. A blank-form book or pad, comprising 95 a plurality of superposed form sheets having a line of weakening near one end, notches in the top and bottom edges of the sheets, means binding the sheets together at their edges at the vertical sides of the pad, 100 at said end and between said end and said notches, said binding extending to the notches and including the portion of the sheet between the same and said line of weakening, said portion of the sheet being of such shape as to receive, and containing when padded, matter validating the sheet for use, a complete numeral printed at one portion of the sheet visible when regularly 105 or irregularly detached, and a safety-numeral printed partly at one side and partly at the other side of one of said notches and said line of weakening being located a substantial distance to the rear of the front end 110 of the binding.

4. A blank-form book or pad, comprising 115 a plurality of superposed form sheets of elongated form, bound on one end and on a portion only of the two adjacent vertical edges, and having the fourth edge unbound, and a line of weakening transversely of the sheets near said end and between the vertical bound edges and said line of weakening being located a substantial distance to the rear 120 of the front end of the binding.

5. A blank-form book or pad, comprising 125 a plurality of superposed form sheets bound on one vertical edge and on a portion only of the two adjacent vertical edges, and having the fourth edge unbound, and having a

line of weakening removed from said end and extending transversely of the sheet between said adjacent vertical edges, and having a blank space on the sheet between the 5 ends of the binding and said line of weakening and said line of weakening being located a substantial distance to the rear of the front end of the binding.

In testimony that I claim the foregoing as my invention, I have signed my name in presence of two subscribing witnesses.

ALEXANDER M. SINCLAIR.
